United States Patent Office

Des. 210,304
Patented Feb. 27, 1968

210,304

CHOCK

Carl B. Davis, 2333 S. Raleigh St.,
Denver, Colo. 80219

Filed Mar. 15, 1967, Ser. No. 6,229

Term of patent 14 years

(Cl. D41—1)

Fig. 1

Fig. 2

Fig. 3

Fig. 4

FIG. 1 is an isometric front view of the chock;
FIG. 2 is an isometric rear view thereof;
FIG. 3 is an isometric bottom view thereof; and
FIG. 4 is a longitudinal sectional view as taken from
the indicated line 4—4 at FIG. 2.

I claim:

The ornamental design for a chock, as shown.
